CLAIM

The ornamental design for an umbrella hub as shown and described.

DESCRIPTION

FIG. 1 shows an umbrella hub embodying the new design thereof, shown in the context of an umbrella.

FIG. 2 is a perspective view of the umbrella hub design illustrated in FIG. 1, a battery assembly shown in dash.

FIG. 3 is a perspective view of the umbrella hub design illustrated in FIG. 1.

FIG. 4 is a front view of the umbrella hub design of FIG. 1.

FIG. 5 is a rear view of the umbrella hub design of FIG. 1.

FIG. 6 is a first side view of the umbrella hub design of FIG. 1.

FIG. 7 is a second side view of the umbrella hub design of FIG. 1.

FIG. 8 is a top view of the umbrella hub design of FIG. 1; and,

FIG. 9 is a bottom view of the umbrella hub design of FIG. 1.

All features in broken lines are for the purpose of illustrating environmental structure and form no part of the claimed subject matter.

1 Claim, 7 Drawing Sheets
